United States Patent Office

Des. 214,730
Patented July 22, 1969

214,730

FIRE HYDRANT

Edward Page, Walnut Creek, Calif., assignor to M. Greenberg's Sons, Inc., San Francisco, Calif., a corporation of California

Filed Oct. 23, 1968, Ser. No. 14,130

Term of patent 14 years

Int. Cl. D23—01

U.S. Cl. D23—12

FIG. 1

FIG. 3

FIG_4

FIGURE 1 is a front elevational view of a fire hydrant showing my new design;

FIGURE 2 is a rear elevational view thereof;

FIGURE 3 is a right side elevational view thereof;

FIGURE 4 is a left side elevational view thereof;

FIGURE 5 is a top plan view thereof; and

FIGURE 6 is a bottom plan view thereof.

The dominant features of my design reside in the portions shown in full lines.

I claim:

The ornamental design for a fire hydrant, as shown and described.
